UNITED STATES PATENT OFFICE.

SUMMERS BROWN, OF LONDON, ENGLAND.

FRAME FOR USE WITH ROTARY DUPLICATING OR PRINTING MACHINES AND THE LIKE.

No. 825,186.

Specification of Letters Patent.

Patented July 3, 1906.

Application filed November 13, 1905. Serial No. 287,081.

To all whom it may concern:

Be it known that I, SUMMERS BROWN, residing at 40 Whitecross street, London, England, have invented a certain new and useful

5 Improvement in Frames for Use with Rotary Duplicating or Printing Machines and the Like; and I do hereby declare the following to be a full, clear, and exact description of the invention, such as will enable others skilled 10 in the art to which it appertains to make and use the same.

My invention consists in an improved detachable frame for use with rotary duplicating or printing machines operated by hand or 15 power and fitted with an automatic feeding device or otherwise.

The great difficulty with rotary duplicating or printing machines having automatic feeding devices as at present constructed is 20 that the absolute feed of one sheet only at a time to the printing-roller cannot always be relied upon, two or more sheets being frequently delivered, involving much loss of time and waste of paper. My invention when 25 attached to the feeding-board of such machines as are suitably constructed for my purpose entirely overcomes this difficulty. Its construction, application, and operation will be readily understood by reference to the 30 annexed drawings, in which—

Figure 1 is a plan of the frame. Fig. 2 is a side sectional elevation, the dotted lines showing diagrammatically its application and operation. Fig. 3 is a view similar to 35 Fig. 1 of a modified form of a frame.

In the drawings, 1 is the feeding-board common to rotary duplicating or printing machines, said board being usually pivoted in a convenient position—as, for instance, at 40 2—and upheld by a spring, counterbalance, or the like in the required position. Upon the board 1 I lay the sheets to be printed, 3, and upon the sheets the frame 4, made of wood, metal, or other suitable material and fitted 45 with a stop 5 at the end nearest the printing-roller. The frame is formed with a widened opening 5^b at a suitable distance from the stop 5 to allow the sheet to be fed forward over it, and in some cases I may mount intermediate bars 4^b, as shown in Fig. 3. To prevent the frame from moving, I may employ pins 6, passing through clearance-holes 7,

formed in the cross-bar 4^a of the frame 4, into the feeding-board 1, or I may secure the frame to the board in any other suitable 55 manner.

The operation of my invention will be understood by means of the diagrammatic view shown in dotted lines and forming part of Fig. 2, which view is merely inserted to make 60 clear such operation and may vary in many ways, depending upon the particular make of the duplicator or printing-machine and the feeding device to which it may be attached. 9 is the printing-cylinder, 10 the gripping- 65 roller, and 11 the feeding-arm pivoted at 12, to which a rocking motion may be imparted by any suitable means for feeding the sheet. The upper sheet 3^a of the paper to be printed, 3, is always below the level of the edge of stop 70 5^a, forming the end of the frame 4. When the feeding-arm 11 or its equivalent device, depending upon the make of the machine, engages with the sheet 3^a, it is forced forward against the edge of the stop 5^a and is first 75 slightly bent upward, as at 3^b, and then releasing itself from the edge 5^a is forced forward between the roll-cylinder 9 and gripping-roller 10, the effect being that only one sheet at a time can be fed to the printing-cylinder, 80 the frame sinking toward the feeding-board as the sheets are used and its alignment being preserved by the stop and pins or equivalent securing the same to the feeding-board. 85

What I claim as my invention, and desire to secure by Letters Patent, is—

1. In combination with a rotary duplicator or printing-machine fitted with an automatic feeding-board, a detachable frame 90 formed with a front stop and resting upon the top sheet of the paper to be printed, the widened opening behind said stop and means for securing said frame to the feeding-board in the way and manner described. 95

2. In combination with a rotary duplicator or printing-machine, a frame having a stop, the height of which is automatically adjusted by the number of sheets of paper and maintained by the sinking of the frame as 100 said sheets are fed forward in the way and manner described.

3. In combination with a rotary duplicator or printing-machine having an automatic

2
feeding-board, a detachable frame having a front stop and additional bars 4^b and resting on the top sheet of the paper to be printed and being also provided with an opening behind said stop and with means for securing said frame to the feeding-board substantially as set forth.

In witness whereof I have hereunto signed my name in the presence of two subscribing witnesses.

SUMMERS BROWN.
